UNITED STATES PATENT OFFICE.

GEORGE H. CARLSON, OF ROCKFORD, ILLINOIS, ASSIGNOR TO REDIN, EKSTROM & CO.,
OF ROCKFORD, ILLINOIS, A CORPORATION OF ILLINOIS.

ROUTING MACHINE.

Application filed March 22, 1926. Serial No. 96,386.

The present invention relates to wood working machines and has particular reference to machines for routing or grooving boards.

The object of the invention is to provide an improved machine for forming parallel grooves in boards having a plurality of vertically disposed spindles and a novel means for mounting the spindles so as to facilitate adjustment of the cutting tools carried by said spindles.

Other objects and advantages will become apparent from the following detailed description taken in connection with the accompanying drawings in which,

Figure 1 is a front elevational view of a machine embodying the features of the present invention.

Figs. 2 and 3 are sectional views taken along the lines 2—2 and 3—3 of Figure 1.

Fig. 4 shows a board which has been grooved by the present machine.

While I have shown in the drawings and will herein describe in detail the preferred embodiment of the invention, it is to be understood that I do not intend thereby to be limited to the particular form disclosed but aim to cover all modifications and alternative constructions falling within the scope of the appended claims.

The embodiment of the invention shown herein comprises a horizontally slidable table for supporting the board to be grooved, a plurality of rotary spindles carrying tools projecting upwardly through the table and a clamping device for holding the board upon the table while it is being carried toward and away from the tools. All of these parts are supported by a framework comprising two side standards 10 rigidly connected intermediate their ends by bars 11 and at their upper ends by a rectangularly shaped casting 12 which constitutes the bed of the machine. In the present instance the bed has a rectangular opening the front and rear edges of which are defined by horizontal ledges 13 having flat upper surfaces 14 near their inner edges.

Supported at their opposite ends upon the ledges 13 of the bed are a plurality of spindle carrying bars 15 which are capable of being adjusted transversely of the bed whereby grooves may be spaced any desired distances apart. The bars are also mounted for adjustment longitudinally of the bed

whereby grooves of different lengths may be formed. For this purpose each bar is of rectangular cross section and has a flat under surface which is held firmly against the surfaces 14 of the bed by clamping devices 16 having bolts 16 extending through elongated vertical slots 17 in opposite ends of the bar. The lower ends of the bolts 16 carry U-shaped clamping hooks 18, the long legs of which project into the slots 17 and serve to hold the members in fixed position relative to the bar. The short legs of the hooks are disposed beneath the ledges 13 and are adapted to project into grooves 19 extending longitudinally of the ledges on the underside thereof. At the upper ends, the bolts are equipped with nuts 20 which may be tightened down against the washers 21 to clamp the bar in any desired position. Thus, it will be observed, that the ledges 13 provide for adjustment of the bars transversely of the bed while the slots 17 provide for longitudinal adjustment of the bars.

Threaded into a central vertical opening in each bar 15 is a tubular member 22 which constitutes a bearing housing for a spindle 23 extending therethrough. Each spindle is journaled in ball bearings 24, one of which is mounted in a cap 25 on the lower end of the spindle housing and the other of which is positioned in an enlarged portion of the housing below a shoulder 26 so as to sustain the downward thrust of the spindle. At its upper end, each spindle is equipped with a suitable chuck 27 adapted to hold a cutting bit 28 in vertical position. Threaded onto the housing 22 is a locking nut 29 which may be tightened down against the upper surface of the supporting bar to lock the housing therein after the spindle has been adjusted vertically to form a groove of the desired depth.

Power from an electric motor 30 is applied to the spindles by belts 31 running around pulleys 33 fixed on the lower ends of the spindles. Preferably, the alternate spindles are made in long and short lengths, the pulleys 33 on the short spindles being driven by the upper belt while the longer spindles are driven by the lower belt. To accommodate the two drive belts a double-grooved drive pulley 34 is provided on the motor shaft and double-grooved idler pulleys 35 are adjustably mounted on the rear side of the framework, the belts being passed alter-

nately around these pulleys and the pulleys 33 as is shown in Fig. 2. The belts are tensioned by springs 36 acting on pulleys 37 swingably mounted from the frame. By thus mounting the spindle pulleys in staggering relation on the lower ends of the spindles, it will be apparent that the adjacent spindles may be positioned relatively close to each other without interference of their pulleys. It is possible therefore to cut grooves which are substantially the same length and spaced very close to each other.

The table upon which the board to be grooved is mounted and carried to and from the cutting bits comprises a rectangular frame structure 38 having inturned ledges 39 which support the opposite ends of the cross bars 40. To provide for lateral adjustment of the cross bars corresponding to the positions of the spindles, their ends are clamped to the ledges as by screws 41 extending through the bars and ledges and threading into clamping plates 42. The upper edges of the bars 40 are flush with the top of the table frame and constitute a flat top surface upon which the board may be firmly clamped. It will be understood that the bit 28 to be used in forming a groove will project upwardly above the top surface of the table, this distance determining the depth of the groove to be cut.

Means is provided for slidably supporting the table upon the main framework. This means consists of a carriage comprising two axles 43 connected by plates 44 and equipped at their ends with grooved wheels 45 which roll along the track bars 46 mounted on the side standards 10. The table is provided at its side edges with similar track bars 47 which rest upon the wheels 45. Stops 48 at the forward ends of the tracks 46 and stops 48^a at the rear ends of the tracks 47 serve to limit the forward movement of the carriage relative to the machine frame. 49 is an adjustable stop which limits the rearward travel of the table thereby determining the length of the grooves.

To hold the board firmly upon the table while it is being grooved, any suitable clamping means may be employed. The means shown herein comprises two standards 50 upstanding from the side edges of the table and carrying slideable bearing blocks 51 in which eccentrics 52 on a shaft 53 are journaled. A T-shaped clamping bar 54 is slidably mounted in the standards 50 and is pressed upwardly against the bearing blocks by springs 55. 56 is a hand screw for adjusting the height of the blocks 51 so that boards of different thicknesses may be accommodated.

In operation, the spindles to be used in grooving the board are equipped with bits of the proper sizes and adjusted to the proper height above the table surface. The

spindle supporting bars are then adjusted on the bed so that the grooves will be properly spaced laterally and of the desired length. The tools are thus set for operation and the motor is started.

With the table pulled forwardly as shown in Fig. 3, the operative places the board to be grooved upon the table with its rear edge abutting against adjustable stops 57 and pulls down a hand lever 58 which causes the bar 54 to clamp the board upon the table as shown in Fig. 3. Grasping the forward end of the table the operative slowly pushes the table rearwardly until the forward edges of the board have passed the tools or the table strikes the stop 49 which has been previously adjusted to limit the length of the grooves. The table is then pulled forwardly and the grooved board is removed from the clamping device. Fig. 4 shows a board which has been grooved by the present machine illustrating the formation of grooves of different lengths, and of different distances apart.

It will be apparent that the machine thus provided is capable of cutting grooves in boards with speed, accuracy and efficiency and with very little effort on the part of the operative.

I claim as my invention:

1. A machine for grooving boards comprising, in combination, a frame supporting a bed having opposite front and rear ledges, a plurality of bars supported at their opposite ends on said ledges, each of said bars having elongated vertical slots at opposite ends, devices operable to clamp the ends of said bars against said ledges including bolts extending through said slots, a vertically disposed bearing housing threaded through each of said bars, a spindle journaled in each of said housings and carrying a cutting tool at its upper end and a drive pulley at the lower end, belt driving means for said pulleys, a table mounted to slide horizontally on said frame, and means for clamping a board to be grooved upon said table.

2. A machine for grooving boards comprising, in combination, a frame having a horizontally disposed bed with an opening therein, a table mounted on said frame above said bed, a plurality of bars extending across said opening and having their opposite ends clamped to said bed and adapted to be adjusted longitudinally and transversely of the bed, a vertical bearing housing threaded through the center of each of said bars, means for locking each housing against movement in its bar, a spindle journaled in each of said housings and carrying a tool projecting above the upper surface of the said table, and driving means associated with the lower ends of said spindles.

3. In a multiple spindle grooving machine, a frame providing a bed having opposed parallel ledges, a plurality of tool-carrying spindles, and means for mounting 5 said spindles on said bed for adjustment transversely and longitudinally thereof, comprising a plurality of bars, each supporting one of said spindles and having its opposite ends resting upon said ledges, said bars having elongated vertical slots at opposite ends, rods extending through said slots, and clamping members at opposite ends of each rod one engaging the upper surface of the bar and the other engaging the underside of 10 one of said ledges.

4. In a multiple spindle grooving machine, a frame providing a horizontal bed having an opening therein, a plurality of vertically disposed tool carrying spindles 20 and means for mounting said spindles in said opening for movement longitudinally and transversely of the bed comprising a plurality of bars, each carrying one of said spindles and having elongated vertical slots 25 at opposite ends, and bolts extending through said slots and having means at their opposite ends for clamping the ends of said bars to the bed at the edges of said opening.

5. In a machine of the character described, 30 a frame having an opening therein, a spindle carrying a cutting tool at one of its ends, means for adjustably mounting said spindle in said opening comprising a bar having an elongated slot at one end, a bolt extending 35 through said slot, means on the ends of said bolt to clamp said bar securely to said frame at the edge of said opening, and a bearing housing for said spindle threaded into said bar.

40 6. A machine for forming parallel grooves in the surface of a board comprising, in combination, a frame having a bed with an elongated opening therein, a table upon which the board is clamped while it is being grooved, said table being mounted to slide forwardly and backwardly on said frame, a plurality of bars extending across said opening having their opposite ends clamped to said bed whereby to permit adjustment of 45 the bars longitudinally and transversely of said opening, a spindle rotatably mounted on each of said bars and extending upwardly through said opening, and tools on said spindles projecting above the upper surface 50 of said table.

7. In a machine of the character described, 60 a frame providing a horizontal ledge, a plurality of tool-carrying spindles, and means for mounting said spindles for adjustment transversely and longitudinally of said ledge comprising a plurality of bars each supporting one of said spindles and having a longitudinally extending slot therein providing for adjustment of the spindle transversely of said ledge, bolts extending 65

through the slots in said bars, and clamping hooks on the ends of said bolts engaging said ledge and providing for adjustment of said bars longitudinally of the ledge.

8. A machine for forming parallel grooves in a board comprising, in combination, a frame, a plurality of spindle supporting devices carried by said frame, a rotary tool-carrying spindle mounted on each of said supporting devices for axial adjustment, said supporting devices being arranged for adjustment perpendicular to the axes of the spindles in one direction to provide for lateral spacing of the grooves and in another direction whereby grooves of different lengths may be formed.

9. A machine for forming parallel grooves in a board comprising, in combination, a frame, and a plurality of tool-carrying spindles each mounted on said frame for axial adjustment whereby grooves of different depths may be cut, said spindles also being adapted to be adjusted transversely in one direction to provide for lateral spacing of the grooves and in another direction whereby grooves of different lengths can be formed simultaneously.

10. A machine for forming grooves in a board comprising, in combination, a frame, and a plurality of tool-carrying spindles each mounted on said frame for axial adjustment whereby grooves of different depths may be cut, said spindles also being adapted for adjustment on the frame in a direction perpendicular to their axes to provide for varying the relative lengths of the grooves.

11. In a machine for cutting grooves in a board, the combination of a frame, a table movably mounted on said frame and supporting a board in a fixed plane, a plurality of spindles mounted on said frame for adjustment perpendicular to said board, said spindles also being adapted to be adjusted relative to said board in one direction to vary the lateral spacing of the grooves and in another direction to vary the relative lengths of the grooves, and tools carried by said spindles and projecting through said table into position to engage the under surface of said board.

12. A machine for forming parallel grooves in the surface of a board comprising, in combination, a stationary frame having a horizontal ledge, a table upon which a board may be clamped while being grooved, said table being mounted above said ledge and adapted for horizontal movement back and forth on said frame, a plurality of bars supported by said ledge and adapted for horizontal adjustment thereon transversely and longitudinally of said table, individual means for each of said bars operable to clamp said bars in adjusted position on said ledge, a plurality of vertically

disposed spindles each rotatably mounted on one of said bars, and tools each carried on by one of said spindles with its cutting end projecting above the upper surface of said table.

13. A machine for forming parallel grooves in the surface of a board comprising, in combination, a frame, means for supporting a board to be grooved, a plurality of rotary spindles arranged in parallel relation and extending substantially perpendicular to the plane of a board placed on said supporting means, rotary cutting tools one on each of said spindles, a plurality of means on said frame each supporting one of said spindles for individual adjustment relative to the other spindles in a direction to vary the length of the groove to be cut thereby with respect to the grooves to be formed by

20 the tools of the other spindles.

14. A machine for forming parallel grooves in the surface of a board comprising, in combination, a frame, means for supporting a board to be grooved, a plurality of rotary spindles arranged in parallel relation and extending substantially perpendicular to the plane of a board placed on said supporting means, rotary cutting tools one on each of said spindles, a plurality of means on said frame each supporting one of said spindles for individual adjustment relative to the other spindles in a direction to vary the lateral spacing and in another direction to vary the length of the groove to be cut thereby with respect to the grooves to be cut by the tools on the other spindles.

In testimony whereof, I have hereunto affixed my signature.

GEORGE H. CARLSON.
